UNITED STATES PATENT OFFICE.

JOSEPHINE MÜLLER, OF NEW YORK, N. Y.

BUILT-UP MATERIAL FOR BELTS AND THE LIKE.

No. 904,350.

Specification of Letters Patent.

Patented Nov. 17, 1908.

Application filed October 15, 1907. Serial No. 397,501.

To all whom it may concern:

Be it known that I, JOSEPHINE MÜLLER, a citizen of the United States, and a resident of the city of New York, borough of Manhattan, in the county and State of New York, have invented a new and useful Improvement in Built-Up Material for Belts and the Like, of which the following is a full, clear, and exact description.

- 10 The purpose of the invention is to provide a built-up material in which the major portion of the warp consists of ribbons of oil-cloth, patent-leather, felt or similar material, the glazed or finished faces of which are 15 their outer faces and in which the weft consists of cord or braid, whereby to provide a fabric which when single ribbons are employed is especially adapted for use as the body portion for bags and like articles, and 20 wherein when the ribbons are used double or are placed back to back, a fabric is provided which may be equally finished on both faces, being especially adapted as material for 25 waist belts.
- 25 A further purpose of the invention is to provide a material of the character described which may be made exceedingly attractive and durable and which will wear smoothly and adapt itself readily to the human form 30 at the waist.

The invention consists in the novel construction and combination of the several parts, as will be hereinafter fully set forth and pointed out in the claims.

- 35 Reference is to be had to the accompanying drawings forming a part of this specification, in which similar characters of reference indicate corresponding parts in all the figures.
- 40 Figure 1 is a plan view of the improved material; Fig. 2 is a longitudinal section taken practically on the line 2—2 of Fig. 1; Fig. 3 is a longitudinal section taken substantially on the line 3—3 of Fig. 1; and 45 Fig. 4 is a longitudinal section through the material constructed with a single finished face.

The warp of the material consists of ribbons A, which ribbons are preferably placed back to back with their finished or glazed surfaces facing outward. These ribbons are made from oil-cloth, glazed leather or similar material. The warp of the material further consists in fabric threads B, any 55 desired number of which being interposed

between the longitudinal edges of the ribbons A, as is clearly shown in Fig. 1.

The weft C of the material consists of a fabric cord or braid, either flat or round, and at the selvage portion c the warp threads, 60 which are designated b to distinguish them from the corresponding threads between the ribbons, are of greater number than the said intermediate warp threads B, as clearly shown in Fig. 1. Preferably the series of 65 warp threads B are few in number so as to bring the opposing longitudinal edges of the ribbons A as close together as is consistent with the flexibility of the material, the said warp threads in Fig. 1 being exaggerated. The ribbons A are shown as passed under two weft threads and then over two weft threads, but such arrangement may be changed or varied; and preferably the warp threads B and b are made to pass over a 70 single weft thread and under the next and so on, as is shown in Fig. 3.

As will be observed by referring to Fig. 2, read in connection with the foregoing description, the material produced is equally 80 finished upon both faces, rendering it reversible, and that it is capable of being highly ornamental by using different colors or characters of weft threads. The material is very durable owing to the warp ribbons 85 employed in its construction.

In Fig. 4 I have illustrated the material as provided with but one finished face, since single warp ribbons A are used, and in this respect only the material shown in Fig. 4 90 differs from that illustrated in the other views. This material may be made upon looms, crochet machines, knitting machines, or any machines adaptable to the purpose, and may be made in any desired shape, as 95 for example, when woven into belt form, it can be graduated from an inch, more or less, at the end to four inches, more or less, at the center; and the material may be used for ribbons or as a braid, and the warp may 100 be of any material dressed or undressed.

Having thus described my invention, I claim as new, and desire to secure by Letters Patent,

1. A built-up material consisting of a 105 warp of flat strips, intermediate warp threads extending parallel with said flat strips and between the same, and weft threads woven through said strips and said threads and forming a fabric therewith.

2. A built-up material consisting of a warp of flat strips, intermediate warp threads between said strips, selvage warp threads at the outer edges of the outermost 5 of said strips, and a weft of threads woven through said warp threads and forming a fabric therewith.

In testimony whereof I have signed my name to this specification in the presence of two subscribing witnesses.

JOSEPHINE MULLER.
